UNITED STATES PATENT OFFICE

JOHN T. SORENSEN, OF CHICAGO, ILLINOIS, ASSIGNOR TO ZENITH HEATER COMPANY, OF CHICAGO, ILLINOIS, A CORPORATION OF ILLINOIS

UNIT HEATER

Application filed October 14, 1931. Serial No. 568,781.

This invention relates to new and useful improvements in the structure of unit heaters, and particularly the type of unit heaters adapted for heating the interior of motor vehicles.

The main objects of this invention are to provide an improved one-piece sheet metal shell or casing for the heater core and tanks; to provide a heater shell of this kind capable of being tightly drawn around the heater core and tanks to securely hold the same by friction; to provide a heater shell having an improved arrangement of simple sheet metal bracket arms for mounting the heater on a wall; to provide a unit heater having an improved air deflector capable of rapid and easy angular adjustment; and to provide an improved construction and arrangement of parts of such heaters with a view to simplifying and reducing the cost thereof.

A specific embodiment of this invention is shown in the accompanying drawing in which:

Figure 1 is a front elevation, the dotted portion showing the air deflector adjusted to one of its angular positions.

Fig. 2 is a side elevation of the same showing the improved arrangement of bracket arms and air deflector construction, a portion of the heater casing being broken away.

Fig. 3 is a rear elevation of the same showing the arrangement of bracket arms and motor support, as well as the method of locking the casing shell to frictionally hold the heater core.

Fig. 4 is a perspective view showing the structure of the heater casing and bracket arms. The drive cleat for locking the heater shell is shown detached at the bottom of the view.

Fig. 5 is an enlarged sectional detail showing a means for mounting the deflector on the radiator core.

As shown in the drawing, the improved heater structure comprises a one-piece encasing shell or enclosure band 1, which is formed to fit the contour of the heater tanks and core 2, and is provided with a turn-back edge 3 at each of its ends to receive a drive cleat or locking device 4. The shell 1 is also provided

with a flange 5 on each vertical side portion, to which flange the front plate or casing 6 is secured.

Bracket arms 7 are rigidly secured to the vertical sides of the heater shell 1 in staggered relationship, and are preferably fastened by means of spot welding 8 and riveting 8', the spot welding 8 being done at the forward end of the heater casing in order to provide a smooth interior, offering no obstruction to the heater core when it is being slipped into position. The bracket arms 7 are each provided with a bolting portion or pad 9, in the form of a flange bent in at right angles to the bracket arms 7.

A motor supporting bracket 10 is secured to each of the arms 7, bridging the space therebetween to support a motor 11 and fan 12, the motor 11 being held to the motor bracket 10, in a central position relative to the rear face of the heater core 2, by means of a strap 13.

The heater core 2 is provided with an air vent 14 projecting through the heater shell at 15, and a heating medium inlet 16 and an outlet 17. The heating medium inlet and outlet tubes extend rearwardly for connection to the source of heating medium supply, and the entire weight of the heater structure is carried by the staggered bracket arms 7, avoiding any strain upon the inlet and outlet pipes by vibration of the unit when mounted in a vehicle.

The heater structure is finished off by means of a front or face plate 6, which is bolted to the flanges 5 of the heater shell 1. The plate 6 is preferably an aluminum casting formed to provide a frame around the front face of the core 2 and the heater shell 1.

The improved air deflector 18, as shown, comprises two sheet metal bars, one of which is longer than the other and each of which has its end portions bent so that they lie in parallel planes angularly disposed relative to the plane of the body portion of the sheet metal bars. The sheet metal bars are secured together so that the turned-up ends are equally spaced from each other and lie in parallel planes, and deflector vanes 19 are secured to each of the turned-up ends. The

deflector unit comprising the bent bars 18 and the vanes 19 thereon, is secured to the heater core by means of a hollow internally threaded stud 20 centrally disposed on the heater core and secured thereto by any suitable means.

As shown in Fig. 5, the deflector 18 is adjustably secured to the stud 20 by means of a bolt 21 which is provided with a shoulder 22 above the threaded portion. However, before the deflector 18 is attached to the core, a compressible washer 23, preferably made of rubber or some such resilient material, is slipped over the projecting portion of the stud 20 in order to provide a backing for the deflector. The washer 23 is made thick enough so that when the bolt 21 is screwed into the stud 20 until the stud is engaged by the shoulder 22 it will be substantially compressed and provide a frictional engagement for the bars of the deflector 18. It will be understood that the washer 23 will be wide enough to provide a substantial bearing on the face of the core 2, so that the washer will not be cut by any sharp edges on the core tubes or fins.

Angular adjustment of the deflector 18 is accomplished by merely turning the deflector to the desired position by hand. It is not necessary to loosen the bolt 21 for this operation because the only friction to be overcome when turning the deflector is that offered by the washer 23, which friction, however, is sufficient to prevent the deflector from turning of its own accord or because of vibration of the heater unit to which it is attached. The bolt 21 is secured against turning during the adjustment of the deflector by means of the tight locking engagement of the shoulder 22 against the end of the stud 20.

The heater shell or casing 1 is preferably formed from a single sheet metal band cut to a width sufficient to extend from the front face of the core 2 to the forward end of the motor 11 so that, when the core and its tanks are assembled in the formed shell, an enclosed space will be provided between the rear face of the core 2 and the motor 11 sufficient to completely house or shroud the fan 12 mounted on the forward end of the motor.

The fan shroud not only protects the fan blades and eliminates the danger of the blades catching on the clothing of, or injuring, persons seated near the heater, but also serves to direct the stream of air handled by the fan so that it will all pass through the heater and not be deflected sideways by the resistance offered by the core.

In assembling the unit heater, the heater shell 1, with the brackets 7 and 10 mounted thereon, is slipped over the heater core and tanks 2, and then drawn tightly around the core and locked by means of the drive cleat 4,

which is carried by and embraces the turned back edges 3 at the ends of the shell 1.

The front plate 6 is then bolted to the flanges 5 of the shell 1, and the fan and motor are mounted on the bracket 10, thus completing the assembly of the heater with the exception of the deflector 18, which is secured to the stud 20 by means of the bolt 21. It is readily apparent that a principal advantage of the improved heater structure lies in the easy and rapid manner with which it is assembled.

The one-piece structure of the heater shell 1, which is tightened around the core and locked by means of a single drive cleat 4, provides a secure frictional support for the heater core and eliminates the necessity of various bolts and strapping means that have heretofore been employed to secure the heater core to the casing structure, and therefore affords an easy assembly operation at a greatly reduced labor cost.

The heater structure is further simplified by the improved arrangement of bracket arms, which are used to fasten the unit heater to its support, and which carry the entire weight of the heater structure.

The two bracket arms 7 are fastened to the heater shell 1 in vertically staggered relation to each other, in order that the heater assembly will be securely supported against vertical as well as horizontal vibration without the use of extra wide and costly bracket arms.

Unit heater structures embodying my herein described invention have the further advantage of being relatively light in weight, due to the fact that a considerable amount of the metal usually employed for such structures has been eliminated.

My improved heater casing is made of relatively light gauge sheet metal, instead of the usual casting or heavy stamped metal casing that has heretofore been employed, and this not only provides a structure of less weight but also materially reduces the cost of manufacture, which is of great importance in a highly competitive field.

Although but one specific embodiment of this invention has been herein shown and described, it will be understood that certain details of the construction shown may be altered or omitted without departing from the spirit of this invention as defined by the following claims.

I claim:

1. A device of the class described comprising a radiator core, a motor, a fan, said fan being mounted adjacent one face of said core, a sheet metal shell comprising a band tensionally surrounding said core, said band being substantially wider than the thickness of said core and extending beyond said core to shroud said fan and means securing the adjoining ends of said shell.

2. In a device of the class described com-

- prising a radiator core, a motor, a fan, a shell laterally surrounding said core, backwardly extending bracket arms secured to the sides of said shell in vertically staggered relation to 5 each other, and means on said arms to support said motor and fan. 70
3. In a device of the class described comprising a radiator core, a motor, a fan, a one-piece sheet metal shell laterally surrounding 10 said core, means securing the adjoining ends of said shell, a frame plate secured to said shell, a backwardly extending sheet metal bracket arm secured on each side of said shell and having one end bent at right angles to 15 provide means to fasten said bracket arm to a support, said arms being disposed on said shell in staggered relation to each other, and means on said arms to support said motor and fan. 80
- 20 4. In a device of the class described comprising a radiator core, a motor, a fan, a one-piece sheet metal shell laterally surrounding said core, turned back edges on the adjoining ends of said shell, a drive cleat enfolding said 25 edges to secure the ends of said shell and cause said shell to tensionally embrace said core, a frame plate secured to said shell, a backwardly extending sheet metal bracket arm secured to each side of said shell and having one end 30 bent at right angles to provide means to fasten said bracket arm to a support, said arms being disposed on said shell in staggered relation to each other, and means carried by said arms to support said motor and fan. 85
- 35 5. A device of the class described comprising a radiator core having a fan mounted adjacent one face thereof and an air deflector mounted adjacent the opposite face, said air deflector comprising a pivotally mounted flat 40 elongated bar having a plurality of spaced relatively narrow vanes transversely attached thereto. 90
6. A device of the class described comprising a radiator core having a fan mounted adjacent one face thereof and an air deflector pivotally mounted adjacent the opposite face, said air deflector comprising an elongated bar having a plurality of fixed vanes attached crosswise thereto, the faces of said vanes being 45 disposed angularly relative to the adjacent face of said bar. 95
7. A device of the class described comprising a radiator core having a fan mounted adjacent one face thereof, a projecting stud fixed 50 to and centrally disposed on the opposite face of said core, and an air deflector pivotally mounted on said stud comprising an elongated bar having a plurality of relatively narrow vanes transversely attached thereto. 100
- 60 8. A device of the class described comprising a radiator core having a fan mounted adjacent one face thereof, a projecting stud fixed 55 to and centrally disposed on the opposite face of said core, and an air deflector pivotally mounted on said stud comprising a flat bar 105
- having a plurality of fixed vanes transversely attached thereto, said vanes being secured to one face of said bar and inclined forwardly therefrom. 110
9. A device of the class described comprising a radiator core, a threaded stud mounted at the front of said core and having a shoulder projecting forwardly from the face thereof, a headed coacting member threaded for engagement with said stud and having a shoulder adapted to engage the shoulder of said stud, an air deflector rotatably mounted on the shoulder of said coacting member, and a yieldable washer disposed over said stud between said deflector and radiator core and extending beyond the shoulder of said stud to frictionally engage said deflector. 115
